UNITED STATES PATENT OFFICE

140,740

DESIGN FOR A WHEELED TRAY OR SIMILAR ARTICLE

Irving Rubin, Brookline, and Julius B. Meltz,
Everett, Mass.

Application November 28, 1944, Serial No. 116,590

Term of patent 14 years

(Cl. D33—14)

To all whom it may concern:

Be it known that we, Irving Rubin and Julius B. Meltz, citizens of the United States of America, residing at Brookline (Chestnut Hill), in the county of Norfolk and Commonwealth of Massachusetts, and Everett, in the county of Middlesex and Commonwealth of Massachusetts, respectively, have invented a new, original, and ornamental Design for a Wheeled Tray or Similar Article, of which the following is a specification, reference being had to the accompanying drawings, forming a part thereof.

Fig. 1 is a side elevational view of a wheeled tray embodying our new design;

Fig. 2 is a front elevational view thereof; and
Fig. 3 is a top perspective view of the device
as seen from its front left-hand corner.

I claim:

The ornamental design for a wheeled tray or
similar article, substantially as shown.

IRVING RUBIN.
JULIUS B. MELTZ.
